UNITED STATES PATENT OFFICE.

WILLIAM C. MEYER, OF BEVERLY, MASSACHUSETTS, ASSIGNOR, BY MESNE ASSIGNMENTS, TO UNITED SHOE MACHINERY CORPORATION, OF PATERSON, NEW JERSEY, A CORPORATION OF NEW JERSEY.

DRIVING AND STOPPING MECHANISM.

1,298,758.

Specification of Letters Patent.

Patented Apr. 1, 1919.

Original application filed July 29, 1913, Serial No. 781,785. Divided and this application filed February 28, 1916. Serial No. 80,908.

To all whom it may concern:

Be it known that I, WILLIAM C. MEYER, a citizen of the United States, residing at Beverly, in the county of Essex and Commonwealth of Massachusetts, have invented certain new and useful Improvements in Driving and Stopping Mechanism; and I do hereby declare the following to be a full, clear, and exact description of the invention, such as will enable others skilled in the art to which it appertains to make and use the same.

The present invention relates to driving and stopping mechanisms, and more particularly to driving and stopping mechanisms adapted for use in high speed machines.

The objects of the invention are to improve the construction and arrangement of driving and stopping mechanisms, and to produce novel and improved mechanism which will act in a uniform and reliable manner to bring the parts of the machine to rest at a predetermined point in a cycle of operations without undue shock, jar or vibration, and without subjecting the parts to excessive strain.

With these objects in view the invention contemplates the provision, in a driving and stopping mechanism of the novel features set forth in the following description and pointed out in the claims, the advantages secured by which will be readily understood and appreciated by those skilled in the art.

The features of the invention are illustrated as embodied in a driving and stopping mechanism of the type comprising a high speed driving mechanism for driving the machine during its normal operation, and a slow speed driving mechanism which is automatically thrown into operation as the machine is disconnected from the high speed driving mechanism, and acts first to reduce the speed of the machine to the speed of the slow speed driving mechanism, and then to drive the machine at slow speed to stopping position. When the machine arrives at the predetermined point at which it is to be stopped it is automatically disconnected from the low speed driving mechanism and its movement is arrested by suitable devices. Certain features of the in-

vention relate particularly to improvements in the mechanism for disconnecting the machine from the slow speed driving mechanism and arresting its movement. The invention also comprises various other improvements in the construction, arrangement and operation of parts of driving and stopping mechanisms.

The present invention is a division of an application Serial No. 781,785, filed July 29th, 1913, for a shoe sewing machine, upon which Patent No. 1,177,581, dated March 28, 1916, was granted and the driving and stopping mechanism is illustrated in the present application as applied to the shoe sewing machine disclosed in said patent. It is to be understood, however, that the invention is not limited in its application to shoe or other sewing machines, but that it may be applied with advantage to various other types of machines.

The invention will be readily understood from an inspection of the accompanying drawings and the following detailed description of the construction illustrated therein.

In the drawings, Figure 1 is a view in side elevation of a shoe sewing machine provided with a driving and stopping mechanism embodying the invention in its preferred form; Fig. 2 is a view in horizontal section taken through the base of the machine; Fig. 3 is a sectional view taken on substantially the line 3—3 of Fig. 1; Fig. 4 is a view, partly in side elevation and partly in section, of the parts shown in Fig. 3, looking from the left; Fig. 5 is a sectional view taken substantially on the line 5—5 of Fig. 4; Fig. 6 is a sectional view taken substantially on the line 6—6 of Fig. 5; Fig. 7 is a detail sectional view illustrating the vibratory lever and co-operating locking bolt, and certain devices for controlling the engagement of the locking bolt with the lever, all of which constitute parts of the stop mechanism; and Fig. 8 is a view similar to Fig. 7, illustrating certain of the parts in different positions.

In the drawings, the invention is illustrated as applied to a shoe sewing machine of the so-called McKay type. The machine is provided with a straight hook needle and

100

devices coöperating therewith to form a chain stitch seam, a rotatable work supporting horn arranged to extend within the shoe, and a presser foot coöperating with the 5 horn to support the work in operating position. The operating parts of the machine are driven from a main or cam shaft 24, and the driving and stopping mechanism is arranged to drive this shaft at a relatively 10 high speed during the sewing operation, and when the seam is completed, to slow down the rotation of said shaft and finally arrest its movement at a point in a cycle of operations when the needle is retracted from the 15 work and the presser foot is free to be lifted to permit the work to be removed.

During the sewing operation, the machine is driven by means of a belt 20 passing about a pulley 22 fast on the main shaft 24 of the 20 machine, and connecting said pulley with a pulley 26 mounted upon a driving shaft 28 located in the base of the machine. The shaft 28 is provided with a loose pulley 30 and with a pulley 32 splined thereto but 25 movable longitudinally thereof, which is driven by a belt from the power shaft. The pulley 26 is loosely mounted on the shaft 28 in front of the pulley 32, and is provided with a ring 34 of friction material for engagement with the adjacent surface of the pulley 32. A fourth pulley 36 is pinned to the shaft 28, and the pulley 26 carries a second ring 38 of friction material for engagement with the adjacent surface of the pulley 30. The shaft 28 is arranged for longitudinal movement in its bearings, and when said 35 shaft is thrust endwise toward the rear of the machine, the pulley 26 is clutched between the opposed faces of the pulley 32 and pulley 36 and thereby caused to rotate with 40 said pulleys. When the shaft is released and allowed to move forwardly or toward the front of the machine, the loose pulley 26 is carried out of clutching engagement with 45 the pulleys 32 and 36. The shaft is actuated to clutch the pulley 26 between pulleys 32 and 36 by suitable connections from a treadle 40 pivoted at the base of the machine. Said connections comprise a bell crank lever 50 pivoted on a stud 42 and provided with an arm 44 which engages the end of the shaft 28. The other arm 46 of the bell crank lever is provided with a forked forward extremity which embraces a rod 48, which is the rod 55 for controlling the device for throwing the stop mechanism into operation. The rod 48 is connected at its lower end with a lever 50, which lever is arranged to be actuated from the treadle. A collar 52 is secured to the 60 rod 48 above the arm 46, and the rod 48 is yieldingly held in raised position by the coiled spring 54. The treadle 40 is pivoted on a horizontal stud 56 carried by a block mounted on a vertical swivel pin 58. This 65 manner of mounting the treadle permits the

treadle to be swung vertically and horizontally. The rearwardly extending arm 64 of the treadle is provided with a lateral projection 60 which is adapted to engage beneath the forward end of the lever 50. When the 70 projection 60 is beneath the end of the lever 50, and the treadle is depressed, the rod 48 is moved downwardly and actuates the bell crank lever 44-46 to thrust the shaft 28 rearwardly and thereby clutch the pulley 26 to 75 the shaft and start the machine into operation. When the forward end of the treadle is released, it is lifted by a coiled spring 62, allowing the rod 48 to be lifted by the spring 54 to release the lever 44-46. The shaft 80 may then move forward to release the pulley 26 from clutching engagement with pulleys 32 and 36. The lateral movement of the rearwardly extending arm 64 of the treadle is limited by the engagement of the end of the 85 arm with stops 66 and 68. These stops are so placed that when the treadle is swung horizontally to bring the end of the arm 64 into engagement with the stop 66, the projection 60 will be brought beneath the lever 50, and when the treadle is swung in the opposite direction to bring the end of the arm 64 into engagement with the stop 68 the projection 60 will be away from beneath the lever 50. To prevent the actuation 90 of the treadle when the treadle is in an intermediate horizontal position a forwardly projecting lug 70 is formed between the stops 66 and 68 on the bracket which supports the lever 50.

In order to permit the work to be removed when the seam has been completed, and another piece of work to be introduced easily and quickly, the machine is provided with mechanism for automatically arresting the rotation of the shaft at the point in the cycle of operations when the needle is retracted out of engagement with the work and the presser-foot is free to be lifted. When the treadle is released at the end of 100 the sewing operation, the mechanism which brings the machine to rest with the parts in proper positions for the removal of the shoe is thrown into operation. This mechanism comprises a friction clutch, one member of which is driven at slow speed in a forward direction, and which, when the clutch members are engaged, first acts as a brake to slow the main shaft down to the slow speed of the forwardly driven member, and then to drive the main shaft at slow speed in a forward direction to bring the devices which finally arrest the rotation of the shaft into engagement. The friction clutch consists of clutch members 72 and 74, of which the member 74 is loosely mounted on the main shaft 24 of the machine, and is driven at slow speed in the same direction as the normal direction of rotation of the shaft 24, by means of a spiral pinion or worm 76, 130

mounted on a hollow shaft or sleeve 78 journaled in bearings 80 in the machine frame. The pinion 76 meshes with the teeth of a spiral or worm gear 82 secured to and preferably formed integral with the clutch member 74. The hollow shaft 78 is continuously driven during the rotation of the main shaft of the machine through a friction clutch connecting said shaft with a pulley 84 which is driven by means of a belt 86 connecting said pulley with the pulley 36 mounted on the driving shaft at the base of the machine. The clutch connection between the shaft 78 and the pulley 84 consists of a clutch member 88 secured to and preferably formed integral with the shaft 78, and a second clutch member 90 carried by the pulley 84. The pulley 84 is journaled upon a rod or shaft 92 extending through the hollow shaft 78, and is confined between collars carried by the rod, as clearly shown in Fig. 5. The clutch members 88 and 90 are engaged and disengaged by the longitudinal movement of the rod within the hollow shaft, as will be presently explained. A brake is provided to arrest the rotation of the shaft 78 and the pinion 76 when the clutch connecting said shaft with the pulley 84 is disengaged. This brake comprises a friction brake member 94 mounted on the shaft 78 to rotate with said shaft. The brake member 94 is connected with the hollow shaft by a pair of blocks or keys 96 secured by screws to the member 94 and arranged to project inwardly through slots 98 in the adjacent portion of the hollow shaft. The brake member 94 is arranged to be engaged with the interior of a brake shoe 100 formed on the frame of the machine when the rod 92 is moved in a direction to disengage the clutch. The inner ends of the blocks 96 extend inwardly to points adjacent to the reduced portion 102 of the rod 92, and the brake member is normally held in position on the rod with the blocks in engagement with the shoulder 104 by a coiled spring 106 surrounding the reduced portion of the rod, and engaging the member 94 outside of the hollow shaft 78, said spring being confined between the member 94 and a collar or washer 108 held by a nut threaded on the end of the rod. The members of the friction clutch are held normally in engagement by means of a second coiled spring 110 surrounding the reduced portion of the rod, and arranged within the coiled spring 106. The coiled spring 110 engages at its inner end the projecting extremity of the hollow shaft 78, and acts to maintain the members 88 and 90 of the friction clutch normally in engagement, and the brake member 94 normally disengaged from the brake shoe. In order to disengage the clutch and engage the brake, the rod 92 is moved longitudinally to

the left (Fig. 5.) This movement of the rod first compresses the coiled spring 110, but does not affect the coiled spring 106 until the friction clutch is disengaged and the members of the brake are brought into engagement, since the spring 106 holds the blocks 96 against the shoulder 104, and the brake member 94 moves with the shaft 78. Further longitudinal movement of the rod, however, after the brake is engaged, causes the compression of both springs, which then serve to engage the members of the brake with considerable pressure. When the rod is released, the springs act together to carry it back in the opposite direction until the shoulder 104 on the rod engages the inner ends of the blocks 96, after which, by the force of the spring 110, the brake member 94, the rod and the spring 106, are moved to the right together a slight distance, sufficient, however, to disengage the brake and engage the clutch.

The clutch member 74 is secured to and preferably formed integral with a sleeve 112 mounted loosely on the main shaft 24 of the machine, and extending from said clutch member toward the rear end of the shaft. The clutch member 72 is secured to a flange extending outwardly from a sleeve 114 loosely journaled on the sleeve 112. The sleeve 114 is free to move longitudinally of the sleeve 112 and of the shaft 24, but is caused to rotate with the shaft by a connection with the pulley 22. In the construction illustrated, the sleeve is provided with a pair of spaced shoulders or abutments 116, which receive between them an arc-shaped lug 118 on the pulley 22. The sleeve is normally held in position longitudinally of the shaft with the clutch members 105 out of engagement by means of a coiled spring 120 surrounding a bolt 122 passing through a hole in the pulley 22 and secured in the sleeve 114, said spring being seated in a recess in the pulley 22, and acting 110 against a washer held by a nut on the bolt.

When the clutch members are engaged, the member 74 at such time being driven at slow speed in a forward direction, they first act as a friction brake to slow down the speed of the main shaft until the shaft and the parts rotating therewith are moving at the same speed as the member 74. The member 74 then acts as a driving member through its engagement with the clutch member 72 to drive the shaft in a forward direction until the devices which finally bring the shaft to rest are brought into engagement. The clutch members are engaged at a definite point in a rotation of the shaft, and the shaft is finally brought to rest at the end of a definite interval after the clutch members are engaged. The mechanism for engaging the members 72 and 74 of the clutch comprise a timing cam con-

sisting of a cam groove 124, formed in the sleeve 114 and engaged by a cam roll 126 carried by an arm 128 of a bell crank lever pivoted on a shaft 130. The other arm 5 132 of the bell crank is provided with a recess 134 adapted to receive a projection 136 at the upper end of a locking pin 138 which is normally held out of engagement with the arm 132, so that during the normal operation 10 of the machine, the bell crank lever is oscillated idly by the cam. The locking pin 138 is mounted to slide vertically in the forward end of a slide 140 mounted to slide horizontally in suitable guides in the frame, and 15 yieldingly held in forward position by a coiled spring 142 interposed between a shoulder on the slide and the end of a screw 144 threaded into the frame, by which the tension of the spring may be adjusted. The 20 slide is provided with an extension 146 projecting rearwardly therefrom through a suitable perforation in the portion of the frame in which the slide is mounted, and the forward movement of the slide in its guides is limited by a nut 148 threaded on the extension 146. By adjusting this nut, the slide may be adjusted to bring the locking pin into a position such that the projection 136 on the locking pin will register 25 with the recess 134 at the proper time in the rotary movement of the main shaft. The locking pin is forced upwardly in the slide by a coiled spring 150 seated in a recess in the slide 140 and engaging the head of the locking pin, and the lower end of the pin is connected with the treadle rod 48 so that the pin is held down with the projection 136 30 out of engagement with the recess 134 while the treadle is depressed and the main driving clutch engaged to drive the main shaft of the machine.

When the projection 136 on the locking pin engages the recess 134 in the arm of the bell crank lever, the lever is no longer free to oscillate, since it is locked to the slide 140, and by the action of the cam groove 124 on the roll 126 carried by the arm of said lever, the clutch member 72 will be forced over into engagement with the clutch member 74 when the roll engages a certain point in the cam groove, which occurs at a definite point in the rotation of the main shaft. After the clutch members have been engaged, the slide 140 will be moved rearwardly in its guides against the tension of the spring 142 by the action of the cam groove 124 on the bell crank lever, and the force with which the clutch members are engaged will depend upon the tension of the spring 142.

The treadle rod 48 is connected with an arm 152 pivoted on a stud 154 mounted in a block 156 secured by a pin 158 to the lower end of the locking pin. A latch 160 is also pivoted on the stud 154, and is arranged to

engage beneath a shoulder 162 on the slide 140 and hold the locking pin from upward movement until the treadle rod has been raised sufficiently to leave the locking pin free to move upward into secure locking engagement with the recess in the arm of the bell crank lever. The latch is disengaged, 70 from the shoulder by the movement of the arm 152, due to the lifting of the treadle rod. A lost motion connection is provided between the arm and the latch to allow the treadle rod to be raised before the latch is disengaged from the shoulder 162. In the construction illustrated, the connection between the arm and the latch consists of a 75 pair of shoulders formed on the hub of the arm adapted to engage corresponding shoulders on the hub of the latch. These shoulders are arranged so that when the arm is moved in either direction there is a certain 80 amount of lost motion of said arm before the latch is actuated by the arm. When the treadle is depressed, the arm 152 swings down until one of the shoulders on its hub engages the opposed shoulder on the hub of the latch, after which the continued downward movement of the treadle acts to draw the locking pin down against the tension of the spring 150. During this movement of the locking pin the latch slides down along 85 the outer face of the shoulder 162 and finally swings inwardly beneath said shoulder. When the treadle is released, the treadle rod first moves upwardly, swinging the arm 152 upwardly therewith without affecting the locking pin until the shoulder on the hub of the arm engages the opposed shoulder on the hub of the latch. The latch is then 90 swung outward from beneath the shoulder 162, leaving the locking pin free to be 95 forced upward by the spring 150.

Mechanism is provided for timing the engagement of the locking pin with the arm 132 of the bell crank lever, so that the locking pin will not move into engagement with 100 said arm until the arm is in a position substantially such that the recess 134 registers with the projection on the locking pin. This insures a secure locking engagement between the locking pin and the arm. This 105 mechanism is illustrated particularly in Figs. 7 and 8. The block 156 extends upwardly along the end of the slide 140, and a second block 164 is pivoted to the block 156 on a stud 166. The block 164 is forced in a 110 direction to bring the said block up against the end of the slide 140 by a spring 168 coiled about the stud 166 and engaging a pin secured in said block. A third block 170 is pivoted on a stud 170^a at the upper 115 end of the block 164, and is normally held down against the upper end of the block 164 by a spring-pressed pin 172, the pointed extremity of which engages a recess in said block. When the locking pin is drawn down 120

130

by the depression of the treadle, the block 164 is swung outwardly away from the end of the slide 140 by the engagement of a shoulder 174 on the forward end of the slide 5 with a shoulder 176 on the block 164. When the latch 160 is released from beneath the projection 136, and the locking pin is forced upward by the spring 150, the shoulder 176 is disengaged from the shoulder 174, and 10 the block 164 swings inwardly under the influence of the spring 168 and brings up against the end of the slide. The block 164 is provided with a shoulder 178 which is adapted to engage beneath a shoulder 180 15 formed on the forward end of the slide 140, when the block 164 is swung inwardly into engagement with the slide. The engagement of the shoulder 178 with the shoulder 180 prevents the locking pin from being forced 20 upwardly while they are engaged. The block 170 projects above the upper face of the slide 140, and the arm 132 of the bell crank lever operates close to the upper face of the slide. When the arm 132, during the 25 oscillatory movement of the bell crank lever, arrives in a position such that the recess 134 registers with the projection 136, the arm 132 strikes the inner face of the block 170 and pushes said block and the block 164 on 30 which it is mounted, away from the end of the slide, thereby disengaging the shoulders 178 and 180, and permitting the locking pin to be forced upwardly to engage the projection 136 in the recess 134. 35 When it is desired to stop the machine without throwing the stop mechanism into operation, the block 170 may be swung about its pivotal connection with the block 164 by a manipulation of the arm 182 formed on 40 said block, the block then being held in position by the engagement of the pin 172 in a second recess in the block. When the block has been thus positioned it will be out of the path of the arm 132 of the bell crank lever 45 when the block 164 swings in against the end of the slide 140 to bring the shoulder 178 beneath the shoulder 180. The engagement of these shoulders will prevent the locking pin from being forced upward into 50 locking engagement with the arm 132 of the bell crank lever, and the machine is then allowed to slow down gradually until it comes to rest. 55 The cam groove 124 is preferably timed so that the arm 132 of the bell crank lever is moved into a position to bring the recess 134 into registration with the projection 136 just as the roll 126 arrives at an idle portion of the cam groove, thereby allowing 60 the shaft to rotate a certain interval after the projection 136 is engaged in the recess 134, before the clutch members are engaged. This permits the projection 136 to become firmly seated in the recess 134 before the cam 65 acts to engage the clutch members.

After the slow speed clutch members 72 and 74 are engaged and the shaft has been slowed down to the speed of the slow speed driving member 74, and while it is being driven at slow speed in a forward direction 70 by said member, the stopping devices which finally bring the shaft to rest are brought into engagement. One of these devices is carried by one of the driven parts, and the shaft is disconnected from the driving mechanism 75 and its rotation arrested by mechanism which is actuated by the movement of the positively driven stopping device. The clutch members 72 and 74 are still engaged when the main shaft is brought to rest, and 80 the rotation of said shaft is arrested by disengaging the clutch which connects the hollow shaft 78 with the pulley 84 and engaging the brake member 94 with the brake shoe 100 to stop the rotation of said latter shaft 85 and the pinion 76. The stopping devices through the engagement of which the main shaft is finally brought to rest comprise a finger or shoulder 184 carried at the forward end of an arm 186 and adapted to be 90 engaged by a projection or lug 188 secured to or formed integral with the flange on the sleeve 114. The arm 186 is mounted for movement to carry the shoulder 184 into and out of the path of the lug 188, and to this 95 end is secured to a rock shaft 190 journaled in an arm 192 which is pivoted on a shaft 194. When the locking pin is in lowered position with the projection 136 out of engagement with the recess 134, the arm 186 100 is held down so that the shoulder 184 is out of the path of the lug 188 by a block 196 secured to the lower end of the locking pin, which engages a roll 198 carried by an arm 200 secured on the rock shaft 190. When 105 the locking pin is forced upward to engage the projection 136 in the recess 134, the arm 186 is swung upwardly to bring the shoulder 184 into the path of the lug 188 by a tension spring 202. The arm 192 extends downwardly beyond the shaft 190 into position 110 to engage the end of the rod 92. When the lug 188 engages the shoulder 184 on the arm 186, it carries the arm 186 to the left (Fig. 3), thereby swinging the arm 192 to the left 115 about the shaft 194 and engaging the end of the arm 192 with the end of the rod 92. The rod is thereby thrust longitudinally against the tension of the spring 110 in a direction 120 to disengage the clutch members 88 and 90, 120 and to engage the brake member 94 with the brake shoe 100. After the brake is engaged, further movement of the rod 92 takes place against the tension of both the springs 110 and 106, thereby forcing the brake members 125 more firmly into engagement. The springs 110 and 106 cushion the action of the stopping devices so that the parts are brought to rest without shock or jar and without excessive strain on any of the parts. 130

When the forward rotation of the shaft has been arrested, the parts are securely locked together, thereby preventing recoil.

It will be obvious that the lug 188 will engage the shoulder 184 at the end of a definite interval after the members of the slow speed clutch are engaged, and the main shaft will be stopped at a definite point in its rotary movement. The cam groove 124 and the lug 188 are relatively arranged so that the interval between the engagement of the members of the slow speed clutch and the engagement of the stopping devices is sufficient to insure that the shaft will be slowed down to the speed of the driving member of the slow speed clutch and will be driven thereby at slow speed before the stopping devices are engaged.

In order to prevent breakage of the parts, 20 in case the stop mechanism fails to act properly and the shaft is not slowed down to the speed of the driving member of the slow speed clutch when the lug 188 engages the shoulder 184, a projection 204 is formed 25 on the arm 186 and is provided with an inclined face 206. If the shaft and the parts rotating therewith are moving at a higher speed than the speed of rotation of the slow speed driving clutch member when 30 the lug 188 engages the shoulder 184, the arm 186 will be carried over farther to the left than under normal conditions and the inclined face 206 of the projection 204 will be brought into engagement with an inclined 35 face 208 on the frame, and the arm 186 will be thrown down so as to disengage the shoulder 184 from the lug 188 and allow the shaft to make another rotation before it comes to rest.

40 Having explained the nature and object of the invention, and having specifically described mechanism embodying the invention in its preferred form, what is claimed is:—

1. A driving and stopping mechanism, 45 having in combination, a shaft, high speed driving mechanism therefor, a slow speed driving member for the shaft, means for disconnecting the shaft from the high speed driving mechanism and connecting it with 50 the slow speed driving member, means for actuating the slow speed member, and means for disconnecting the slow speed member from its actuating mechanism and arresting its rotation while the shaft remains in connection with the slow speed member to stop 55 the rotation of the shaft.

2. A driving and stopping mechanism, 60 having in combination, a shaft, high speed driving mechanism therefor, a slow speed driving clutch member for the shaft, a slow speed driven clutch member, means for engaging the slow speed clutch members upon disconnecting the shaft from its high speed driving mechanism, means for actuating the 65 slow speed driving clutch member, and

means for disconnecting the slow speed driving clutch member from its actuating mechanism and arresting its rotation while the slow speed clutch members remain in engagement to arrest the rotation of the shaft. 70

3. A driving and stopping mechanism, having in combination, a shaft, high speed driving mechanism therefor, a slow speed driving friction clutch member and a co-operating clutch member for slowing down 75 the shaft and driving it forward at slow speed to stopping position, means for engaging the members of the slow speed clutch when the shaft is disconnected from the high speed driving mechanism, means for actuating the slow speed driving clutch member, and means for disconnecting the slow speed driving clutch member from its actuating mechanism and stopping its rotation at the end of a predetermined interval after the 80 engagement of the clutch members and while they remain in engagement to stop the rotation of the shaft.

4. A driving and stopping mechanism, 90 having, in combination, a shaft, high speed driving mechanism therefor, a slow speed driving friction clutch member and a co-operating clutch member for slowing down the shaft and driving it forward at slow speed to stopping position, means for actuating the slow speed driving clutch member, means for engaging the slow speed clutch members at a predetermined point in the rotation of the shaft upon disconnecting the shaft from the high speed driving mechanism, and means for disconnecting the slow speed driving clutch member from its actuating mechanism and arresting its rotation at the end of a predetermined interval after the engagement of the members of the clutch 100 105 and while they remain in engagement to arrest the rotation of the shaft at a predetermined point.

5. A driving and stopping mechanism, 110 having in combination, a shaft, high and low speed driving mechanism, therefor, means for disconnecting the shaft from the high speed driving mechanism and connecting it with the low speed driving mechanism, and means for finally bringing the shaft to rest while it is driven at slow speed by the low speed mechanism comprising a stop carried by one of the driven parts, a finger arranged to be projected into the path of the stop, and mechanism actuated by said finger for disconnecting the shaft from the low speed mechanism and arresting its rotation. 115 120

6. A driving and stopping mechanism, 125 having in combination, a shaft, high speed driving mechanism therefor, a slow speed driving clutch member and a co-operating clutch member mounted to rotate with the shaft for slowing down the speed of the shaft and driving it at slow speed to stop- 130

- ping position, means for engaging the slow speed clutch members when the shaft is disconnected from the high speed driving mechanism, means for actuating the slow speed 5 driving clutch member comprising a secondary clutch, a brake for arresting the rotation of the shaft, and means for disconnecting the secondary clutch and engaging the brake to bring the shaft to rest.
- 10 7. A driving and stopping mechanism, having, in combination, a shaft, a high speed driving mechanism therefor, a slow speed driving member, means for connecting the shaft with the slow speed member upon dis- 15 connecting it from the high speed driving mechanism, means for actuating the slow speed driving member comprising a clutch, a brake for arresting the rotation of the shaft, and means for disconnecting the clutch and 20 engaging the brake to bring the shaft to rest.
8. A driving and stopping mechanism, having, in combination, a main shaft, high speed driving mechanism therefor, a slow speed driving clutch member for the shaft 25 and a coöperating clutch member fast on the shaft for slowing down the shaft and driving it at slow speed to stopping position, means for actuating the slow speed driving clutch member comprising a worm gear carried 30 thereby, a worm meshing with the worm gear, a worm shaft, a secondary clutch for rotating the worm shaft, a brake for the worm shaft, and means for disconnecting the secondary clutch and engaging the brake 35 while the slow speed clutch members remain in engagement to arrest the rotation of the main shaft.
9. A driving and stopping mechanism, having, in combination, a main shaft, high 40 speed driving mechanism therefor, a slow speed driving clutch member and a coöperating clutch member fast on the shaft for slowing down the shaft and driving it to stopping position, means for actuating the 45 slow speed driving clutch member comprising a worm gear carried thereby, a worm meshing with the worm gear, a worm shaft, a secondary clutch for rotating the worm shaft, a brake for the worm shaft, and means 50 for disconnecting the secondary clutch and engaging the brake while the slow speed clutch members remain in engagement to arrest the rotation of the main shaft comprising a stop carried by one of the parts 55 which are driven by the worm, a stop finger arranged to be projected into the path of the stop, and mechanism operated by the finger for disconnecting the secondary clutch and engaging the brake.
- 60 10. A driving and stopping mechanism, having, in combination, a main shaft, a driving clutch member therefor, a coöperating clutch member mounted on the shaft to rotate therewith, means for actuating the driv- 65 ing clutch member comprising a worm gear carried thereby, a worm meshing with the worm gear, a worm shaft, a secondary clutch for rotating the worm shaft, a brake for the worm shaft, and means for arresting the rotation of the main shaft comprising a stop carried by one of the parts 70 which are driven by the worm, a stop finger arranged to be projected into the path of the stop, and mechanism operated by the finger for disconnecting the secondary clutch and engaging the brake while the first clutch members remain in engagement.
11. A driving and stopping mechanism, having, in combination, a main shaft, a driving clutch comprising a driving clutch member and a coöperating driven clutch member mounted on the shaft to rotate therewith, means for actuating the driving clutch member comprising a worm meshing therewith, a worm shaft, a secondary clutch for rotat- 80 ing the worm shaft, a brake for the worm shaft, and means for disconnecting the secondary clutch and engaging the brake while the first clutch members remain in engagement to arrest the rotation of the main shaft.
12. A driving and stopping mechanism, having, in combination, a shaft, high and low speed driving mechanism therefor, comprising a slow speed driving clutch member 85 and a driven clutch member mounted to rotate with the shaft, means for rotating the driving clutch member comprising a secondary clutch, a brake for the driven member of the secondary clutch, and means for disen- 90 gaging the secondary clutch and engaging the brake while the members of the slow speed clutch remain in engagement to arrest the rotation of the shaft.
13. A driving and stopping mechanism, having, in combination, a shaft, high and low speed driving mechanism therefor, means for disconnecting the shaft from the high speed driving mechanism and connect- 95 ing it with the low speed driving mechanism, means for disconnecting the shaft from the low speed mechanism and arresting its rotation comprising a stop carried by one of the parts driven by the slow speed mechanism, a finger arranged to be projected into the path of the stop, mechanism operated by the finger for disconnecting the shaft from the low speed mechanism and arresting its rotation, and means for projecting the finger into the path of the stop upon disconnecting the shaft from the high and connecting it with the low speed driving mechanism.
14. A driving and stopping mechanism, having, in combination, a shaft, high speed driving mechanism therefor, a slow speed 110 driving member, means for actuating the slow speed member comprising a clutch, a brake for arresting the rotation of the parts driven by the clutch, means for disengaging the clutch and engaging the brake while the 115

- 130

- shaft remains in connection with the slow speed member to arrest the rotation of the shaft comprising a stop carried by one of the parts driven by the clutch, a finger arranged 5 to be projected into the path of the stop, and mechanism actuated by the finger for disengaging the clutch and engaging the brake.
15. A driving and stopping mechanism, having in combination, a shaft, high speed 10 driving mechanism therefor, a low speed driving clutch member and a driven clutch member mounted to rotate with the shaft, means for rotating the driving clutch member comprising a secondary clutch, a brake 15 for arresting the rotation of the parts driven by the secondary clutch, means for disengaging the secondary clutch and engaging the brake while the slow speed clutch members remain in engagement to arrest the rotation 20 of the shaft comprising a stop carried by one of the parts driven by the secondary clutch, a finger arranged to be projected into the path of the stop, and mechanism operated by said finger for disengaging the secondary 25 clutch and engaging the brake.
16. A driving and stopping mechanism, having, in combination, a shaft, high speed driving mechanism therefor, a slow speed driving clutch member and a driven clutch 30 member mounted to rotate with the shaft, means for rotating the driving clutch member comprising a secondary clutch, a brake for arresting the rotation of the parts driven by the secondary clutch, means for disengag- 35 ing the secondary clutch and engaging the brake while the slow speed clutch members remain in engagement to arrest the rotation of the shaft comprising a stop carried by one of the parts driven by the secondary clutch,
- 40 a finger arranged to be projected into the path of the stop, mechanism operated by said finger for disengaging the secondary clutch and engaging the brake, and means to project the finger into the path of the stop upon dis- 45 connecting the shaft from the high speed driving mechanism and engaging the mem- bers of the slow speed clutch.
17. A driving and stopping mechanism, having, in combination, a shaft, high speed 50 driving mechanism therefor, a slow speed driving member, means for actuating the driving member comprising a clutch, a brake for arresting the rotation of the parts driven by the clutch, and means operated 55 through the clutch for disconnecting the clutch and engaging the brake while the shaft remains in connection with the slow speed driving member to arrest the rotation of the shaft.
- 60 18. A driving and stopping mechanism, having, in combination, a shaft, high speed driving mechanism therefor, a slow speed driving clutch comprising a driving clutch member and a driven clutch member, means

for actuating the driving clutch member in- 65 cluding a secondary clutch, a brake for ar- resting the rotation of the parts driven by the secondary clutch, and means operated through the secondary clutch for discon- 70 necting the secondary clutch and engaging the brake while the slow speed clutch mem- bers remain in engagement to arrest the ro- tation of the shaft.

19. A driving and stopping mechanism, having, in combination, a shaft, a driving 75 clutch member therefor, a driven clutch member, means for engaging the clutch mem- bers comprising a cam carried by one of the clutch members, a lever normally oscillated idly by said cam, a locking pin for locking 80 said lever from oscillation to cause the en- gagement of the clutch members, and means for timing the engagement of the locking pin with the lever.

20. A driving and stopping mechanism, 85 having, in combination, a shaft, a driving clutch member and a driven clutch member, means for engaging the clutch members comprising a cam carried by one of the clutch members, a lever normally oscillated 90 idly by the cam and having a recess, a lock- ing pin having a projection thereon for en- gagement with the recess in the lever to lock 95 the lever from free oscillation and thereby cause the engagement of the clutch members, and means for preventing the engagement of the locking pin with the recess until the lever registers with the pin.

21. A driving and stopping mechanism, having, in combination, a shaft, a driving 100 member for the shaft, means for connecting the driving member with and for discon- 105 necting it from the shaft, means for actu- ating the driving member, and mechanism for disconnecting the driving member from its actuating mechanism and arresting its rotation while it remains in connection with the shaft to stop the rotation of the shaft.

22. A driving and stopping mechanism, 110 having, in combination, a shaft, main driv- ing mechanism for the shaft, stopping me- chanism for the shaft arranged to be thrown into operation as the main driving mechanism is disconnected from the shaft, 115 and means arranged for adjustment to pre- vent the throwing of the stopping me- chanism into operation as the main driving mechanism is disconnected from the shaft.

23. A driving and stopping mechanism, 120 having, in combination, a shaft, main driv- ing mechanism for the shaft, stopping me- chanism for the shaft arranged to be thrown into operation upon the disconnec- 125 tion of the driving mechanism from the shaft, a device operating when in one position to prevent the throwing of the stopping mechanism into operation, machine oper-

ated knock-off mechanism for throwing said device out of such position to allow the stopping mechanism to be thrown into operation, and provision for adjustment to render 5 the knock-off mechanism inoperative so that the stopping mechanism is not thrown into operation upon the disconnection of the main driving mechanism from the shaft.

24. A driving and stopping mechanism, 10 having, in combination, a shaft, driving mechanism for the shaft, mechanism for stopping the rotation of the shaft, a stop carried by one of the driven parts, a finger arranged to be projected into the path of 15 the stop, mechanism operated by the finger for throwing the stopping mechanism into operation, and means for throwing the finger out of engagement with the stop when the stop is moving at a relatively high speed 20 at the time of the engagement of the finger therewith.

25. A driving and stopping mechanism, having, in combination, a shaft, a driving clutch member therefor, a driven clutch 25 member, means for engaging the clutch members comprising a cam carried by one of the clutch members, a lever normally oscillated idly by the cam, a locking pin for locking the lever from oscillation to cause the 30 engagement of the clutch members, a latch for preventing the engagement of the locking pin with the lever arranged to be released by the lever, and provision for ad-

justment to render the lever inoperative to release the latch. 35

26. A driving and stopping mechanism having, in combination, a shaft, high and low speed driving mechanism for the shaft, means for throwing the low speed mechanism into and out of operation comprising a 40 normally inoperative cam, means for rendering the cam operative upon the disconnection of the shaft from the high speed driving mechanism, and means arranged for adjustment to prevent the cam from being 45 rendered operative upon the disconnection of the shaft from the high speed driving mechanism.

27. A driving and stopping mechanism having, in combination, a shaft, high and 50 low speed driving mechanism for the shaft, means for throwing the low speed mechanism into and out of operation comprising a normally inoperative cam, a lever normally 55 oscillated idly by the cam, a lock bolt carrier, a lock bolt movably mounted in the carrier for locking the lever to the carrier to render the cam operative, a latch for preventing the engagement of the lock bolt with the lever, and a block adjustably 60 mounted on the latch and arranged when in one position to be engaged by the lever to throw out the latch, and when in another position to lie out of the path of the lever.
